COMBINED RECHARGEABLE PORTABLE RADIO AND SEPARABLE CHARGER

Richard Culbertson, New Hartford, N.Y., assignor to
General Electric Company, a corporation of New
York

Filed Nov. 21, 1966, Ser. No. 4,749

Term of patent 7 years

(Cl. D56—4)

FIG.1

FIG.2

FIG.3

FIG.4

FIG.5

FIG. 1 is a front, top and right side perspective view of a combined rechargeable portable radio and separable charger, showing my new design in assembled position;

FIG. 2 is a right side elevational view, the left side being substantially a mirror image thereof;

FIG. 3 is a front elevational view;

FIG. 4 is a top plan view; and

FIG. 5 is an exploded front, top and right side perspective view thereof.

The legible matter in the drawings is shown in broken line form for illustrative purposes only.

I claim:

The ornamental design for a combined rechargeable portable radio and separable charger, as shown and described.
